(57) **CLAIM**

I claim the ornamental design for a computer equipment support rack for attachment to a workstation, as shown and described.

DESCRIPTION

FIG. 1 is a perspective view of a computer equipment support rack in use with its intended environment shown in broken lines;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a perspective view of a second embodiment of the computer equipment support rack of FIGS. 1-7 in use with its intended environment shown in broken lines;

FIG. 9 is a front elevation view of the second embodiment; and,

FIG. 10 is a rear elevation view of the second embodiment. The broken lines in FIGS. 1-10 are illustrative of an environmental structure only and form no part of the claimed design.
